UNITED STATES PATENT OFFICE.

GEORGE L. DANFORTH, JR., OF CHICAGO, ILLINOIS.

CONSTRUCTION OF OPEN-HEARTH-FURNACE PORTS.

Application filed October 9, 1922. Serial No. 593,277.

To all whom it may concern:

Be it known that I, GEORGE L. DANFORTH, Jr., a citizen of the United States, residing at Chicago, in the county of Cook and State 5 of Illinois, have invented certain new and useful Improvements in the Construction of Open-Hearth-Furnace Ports, of which the following is a specification.

This invention relates to a new and improved construction of open hearth furnace ports and more particularly to a construction involving the use of a plurality of gas ports associated with a damper controlled air port.

15 As is well known in the art, open hearth furnaces are double ended and are reversed in operation, each end serving alternately to introduce the fuel and air and to carry off the products of combustion. The products 20 of combustion largely exceed in volume the incoming air and fuel and consequently the ports must be designed with a view of carrying off the larger volume of the products of combustion. It is, however, necessary 25 for efficient operation that the incoming air and fuel be properly intermingled and controlled to form a relatively short, hot flame properly directed upon the bath of metal in the furnace.

30 Certain furnaces have been designed with damper controlled ports upon each end of the furnace, these ports being closed off upon the incoming end and serving on the outgoing end to aid in carrying off the products 35 of combustion. A furnace of this type is shown in the patent to McKune, No. 1,339,855, dated May 11, 1920. In these furnaces, two dampers are required, one in each of the supplemental discharge passages, and 40 these dampers not only complicate the installation but due to their water-cooling, involve considerable heat losses.

It is desirable in open hearth furnaces to 45 separate the incoming fuel at each end of the furnace into a plurality of small streams since the small streams will more readily mix with the air and will give a more rapid combustion. Another advantage of divided streams lies in their greater efficiency in 50 melting down a charge. A single central flame will be broken up by impinging upon the charge and will be deflected to the walls and roof. This results not only in inefficient heating but in damage to the furnace walls 55 and roof. On the other hand the divided

streams will meet upon the piled up charge and will efficiently melt it down. In the construction of separate ports the furnace side walls may be utilized as port walls so that but little additional brickwork is required over a single port furnace. 60

It is an object of the present invention to provide a new and improved port construction wherein the intermingled fuel and air are introduced in a plurality of streams. 65

It is an additional object to provide a construction of this type wherein additional, selectively enlarged port area is provided for carrying off the products of combustion.

It is an additional object to provide a construction of this type in which the air passages communicate with the fuel and air ports, means being provided for selectively directing the air into the combined ports. 70

Other and further objects will appear as 75 the description proceeds.

I have illustrated a preferred embodiment of my invention in the accompanying drawings, in which—

Figure 1 is a vertical longitudinal section 80 showing one end of my furnace construction;

Figure 2 is a horizontal section taken on line 2—2 of Figure 1;

Figure 3 is a transverse section taken on line 3—3 of Figure 1; and

Figure 4 is a transverse section taken on line 4—4 of Figure 1.

It will be understood that the usual regenerative chambers and passages will be 85 provided in connection with the furnace, but these chambers form in themselves no part of the present invention and have not been shown.

The slag pocket 7 is connected by uptake 90 passage 8 with the central port 9 of the furnace. The gas slag pocket 10 is connected by the passages 11 with the two lateral ports 12. The uptake 8 is connected with the ports 12 by the lateral passages 13, these passages 95 entering the rear of the ports. The central port 9 is controlled by the vertically movable damper 14 which moves in water-cooled guides 15 and is provided with the housing 16 extending above the furnace roof. The 100 nozzles 17 indicated in dotted lines may be provided for the introduction of liquid fuel or coke oven gas, if such fuels are used.

The lateral ports 12 incline inwardly toward the center line of the furnace as best 110

shown in Figure 2 and the furnace walls incline inwardly at 18 to meet the outer wall of the lateral ports so that a substantially continuous wall is formed with the smallest cross-sectional area of the furnace located immediately in advance of the ports.

As shown in the drawings, the invention has been applied to a tilting furnace, the furnace body 19 being separated from the 10 furnace ends containing the ports. Obviously, the invention may be applied to fixed furnaces without change in the port construction from that shown.

In the operation of the furnace, the gas 15 will be preheated in the usual regenerators and will pass up from slag pocket 10 through uptakes 11 into the ports 12. The air will be preheated and reach the slag pocket 7 from the regenerators. From the 20 slag pockets 7, it will pass through uptake 8 into the rear of the port 9. The damper 14 will be lowered to block off the central port and the air will pass through the lateral passages 13 into the rear end of the 25 ports 12. The air will mingle with the gas coming up into the ports and the mixture of air and gas will issue from the mouths of the ports. These ports are the proper size to give an adequately controlled flame and 30 their inward inclination is such as to properly direct the flame upon the bath of metal in the furnace. If it is desired to use coke oven gas or liquid fuel, no gas will come up through the uptakes 11, but the fuel will 35 be introduced through nozzles 17.

Upon the outgoing end of the furnace, the damper 14 will be raised and a portion of the products of combustion will pass 40 through the port 9 directly to downtime 8 and thence to slag pocket 7 and the air regenerators. The remainder of the products of combustion will enter the side ports 12 and of these products of combustion a greater portion will pass down uptakes 11 45 to the slag pocket 10 and thence to the gas regenerators.

By raising the damper 14 upon the outgoing end, the area available for passage of the products of combustion is greatly increased over that provided on the incoming end for the air and fuel. This greater area permits the products of combustion to be carried off without the necessity for the provision of auxiliary draft means. The 55 ports used for the introduction of the air and fuel may be of such area and contour

as to provide an efficient and adequately controlled and directed flame.

I claim:

1. In a reversible regenerative furnace, 60 a plurality of fuel ports located adjacent the side walls of the furnace, an air passage, a discharge port located intermediate said fuel ports, and passages connecting the air passage and fuel ports.

2. In a reversible regenerative furnace, a plurality of fuel ports located adjacent the side walls of the furnace, an air passage, a port located intermediate said fuel ports, 65 passages connecting the air passage and fuel ports, and a damper controlling the intermediate port.

3. In a reversible regenerative furnace, a plurality of fuel ports located adjacent the side walls of the furnace, fuel passages entering the fuel ports, an air passage and a port connected thereto located intermediate the fuel ports and passages connecting the air passage and fuel ports, said passages 70 entering the fuel ports in the rear of the entrance of the fuel passages into said ports.

4. In a reversible regenerative furnace, a plurality of fuel ports located adjacent the side walls of the furnace, an air uptake and 75 a port connected thereto located intermediate said fuel ports and laterally extending passages connecting the uptake and the rear of the fuel ports.

5. In a reversible regenerative furnace, a plurality of fuel ports located adjacent 80 the side walls of the furnace, fuel passages entering the fuel ports, an air passage and a port connected thereto located intermediate the fuel ports, passages connecting the air passage and fuel ports, said passages 85 entering the fuel ports in the rear of the entrance of the fuel passages into said ports, and a movable damper adapted to close the air port.

6. In a reversible regenerative furnace, a 90 plurality of fuel ports located adjacent the side walls of the furnace, an air uptake and a port located intermediate said fuel ports, laterally extending passages connecting the air uptake and the rear of the fuel ports, 95 and a movable damper adapted to close the intermediate port and to deflect the air into the laterally extending passages.

Signed at Chicago, Illinois, this 4th day of October, 1922.

GEORGE L. DANFORTH, JR.
